A. F. ANDERSON

CHAIN HOLDING HOOK STRUCTURE

Filed Nov. 26, 1923

Patented Mar. 24, 1925.

1,530,472

UNITED STATES PATENT OFFICE.

ANDREW F. ANDERSON, OF SPOKANE, WASHINGTON.

CHAIN-HOLDING-HOOK STRUCTURE.

Application filed November 26, 1923. Serial No. 677,005.

To all whom it may concern:

Be it known that I, ANDREW F. ANDERSON, a citizen of the United States, residing at Spokane, in the county of Spokane and 5 State of Washington, have invented new and useful Improvements in Chain-Holding-Hook Structures, of which the following is a specification.

This invention relates to improvements 10 in chain holding hook structures of the reusable type.

The device of my invention is primarily designed for use in holding binder chains about a carload of logs and one of the features 15 consists in a device of this character which is not in any way attached or connected with the car structure.

A further feature resides in means whereby the device can be tripped to release the 20 chain by an operator located at one end of the car so that such operator is free from danger of the falling logs.

My invention resides in features of construction which will be more fully described 25 in connection with the accompanying drawing and which will be more particularly pointed out in and by the appended claims.

In the drawing:

Fig. 1, is a view in side elevation of a car 30 loaded with logs and showing the device of my invention applied to the binding chain, the means for holding the logs on the car not being shown.

Fig. 2, is an enlarged view of the hook structure showing the same in a chain holding 35 position.

Fig. 3, is a similar view showing the structure in a chain releasing position.

Fig. 4, is a fragmentary view partly in 40 section showing the internal means for retaining the parts in the position shown in Figure 2.

Fig. 5, is a view similar to Figure 4, showing 45 how the parts appear when in a released position.

Fig. 6, is a fragmentary view looking from the right of Figure 4.

Like characters of reference designate 50 similar parts throughout the different figures of the drawing.

I have shown the logs 1, mounted on bolsters 2, of a logging car generally indicated at 3. The car may or may not be equipped with bunk pins or any means for 55 preventing the logs from sliding on the bolsters 2, all of which is immaterial to

my invention. What is generally known as the binding chain is designated at 4, and the hook structure of my invention is shown at 5. A trip cord 6, may extend from the hook structure 5, to a point adjacent the end of the car so that an operator may stand in a place of safety when he trips the device and releases the chain 4, to let the logs fall. It will thus be seen that my invention is 65 self contained and is not connected with the car or in any way dependent thereon.

I will next describe the specific construction of my improved hook structure.

The device of my invention comprises 70 pivotally connected members one being a shank member indicated at 7, and the other the bill member which is indicated at 8. One end 9, of the shank member is apertured at 10, for attachment thereto of one end 11, 75 of the chain to be held. One end of the bill 8, is reduced at 12, and apertured to receive a pivot 13, which extends through the forked end 14, of the shank 7. The bill 8, is curved as shown at 15, the construction 80 being such that when the structure is in a chain holding position, it will be disposed at an angle to the chain line or line of stress on the chain 4, as clearly shown in Fig. 2. The bill 8, is forked at 16, to permit a link 85 17, of the chain to be inserted flat-wise into the forked portion, the next link 18 being disposed transversely of the plane of space of the fork and holding the chain in the fork. Now it will be noted that my improved bill 8, is at all times open and never 90 closes against the shank 7. What I will term the chain side of the hook is designated at A, the rear side being indicated at B.

I will next describe the construction of the bill member whereby the same is rendered capable of coaction with a keeper and trip mechanism.

The configuration of the reduced portion 100 12, of the bill 8, is clearly shown in Fig. 4, the back edge of the bill 8, terminating in a keeper engaging shoulder 19. Adjacent shoulder 19, there is formed a semi-circular recess 20, opening toward the rear side B. 105 In this recess is journalled a releasing cam 21, having a periphery which is partly cylindrical as at 22, and a portion which is flat, as indicated at 23. The ends 24, of said cam 21, extend laterally, in the same 110 cross section. A trip arm 25, has a forked end 26 which nest about the reduced por-

tion 12, as shown, and has openings shaped to fit the ends 24, so that the cam 21 will be non-rotatively connected with trip arm 25. It will also be clear that trip arm 25 is pivotally connected with bill member 8. A trip cord 6 is secured to the aperture 27, in arm 25.

My improved keeper is shown in the form of a lever arm 28 having ears 29 which fork 10 a lug 30, formed on shank 7. A pivot pin 31, pivotally unites the keeper 28 with shank 7, and the latter is only slightly recessed to receive the ears 29, thereby permitting the keeper 28 only a very slight movement. 15 The remaining end of the keeper is adapted for engagement with shoulder 19 and for coaction with cam 21. It will be seen that the end 32, of keeper 28, engages shoulder 19 and thereby prevents the bill 8 from 20 swinging from the retaining position shown in Fig. 2, to the releasing position shown in Fig. 3. Now on the left hand face of this end of the keeper 28, is a projection having a slanting face 33 which terminates at 34, 25 and then curves into the keeper 28 as indicated at 35. This projection is provided so that as the edge 36 of the cam advances in a clockwise direction it will have a contacting engagement with keeper 28 sufficiently to 30 move the latter clear from engagement with shoulder 19. After the keeper has been disengaged from shoulder 19, the pull of the chain will move the bill 8 to the extreme position shown in Fig. 3. 35 It will be seen that the forked portion of trip arm 25, will always house the free end of keeper 28, so that when the structure is in a releasing position, the keeper cannot swing downwardly completely out of range of reengagement with cam 21, but is held in fairly close proximity thereto.

It will also be noted that by reason of the fact that trip arm 25, is non-rotatively connected with cam 21, the arm will always, of necessity, be in the correct position shown in Fig. 2, when the hook structure is in a chain retaining position, and will be so held by the keeper 28. This is also due to the fact that the keeper 28 cannot be adjusted 45 into a retaining position until the cam 21 and the arm 25 are in the position shown in Fig. 2.

It is believed that my invention will be fully understood from the foregoing description, and while I have herein shown and described one specific form of my invention, I do not wish to be limited thereto except for such limitations as the claims 55 may import.

I claim:

1. A chain holder comprising a shank connected with one end of the chain, a bill

pivoted to said shank and adapted for releasable connection with the remaining end of said chain, a keeper pivoted to said shank 65 and engaging said bill to retain the latter in a chain engaging position, and a trip arm pivoted to said bill for dis-engaging said keeper from said bill.

2. A chain holder comprising a shank 70 having one end thereof connected to one end of the chain to be held, a bill having a fork on one end and the remaining end of said bill being pivoted to the remaining end of said shank, a strut keeper pivoted to said 75 shank and engaging said bill to retain the latter in a chain holding position, and a trip arm pivoted to said bill for dis-engaging said keeper from said bill.

3. In a chain holding hook structure, the 80 combination with pivotally connected bill and shank members shaped to be disposed at an angle to the chain line when in a chain holding position, and keeper and trip mechanism on that side of the hook structure opposite the chain side for holding said bill in and releasing said bill from a chain holding position.

4. In a chain holding hook structure, the 85 combination with pivotally connected shank and bill members, said bill member having a keeper engaging shoulder, a keeper on said shank member for engagement with said shoulder, a keeper releasing cam rotatable in said bill member for dis-engaging said keeper from said shoulder to release said bill member, and a trip arm carried by said cam for actuating the latter.

5. In a chain holding hook structure, the 90 combination with pivotally connected shank and bill members, a keeper carried by said shank member for holding said bill member in a chain holding position, and a cam trip means on said bill member for releasing 95 said keeper from said bill member.

6. In a chain holding hook structure, the 100 combination with pivotally connected shank and bill members, a keeper carried by said shank member for retaining said bill member in a chain holding position, and cam 105 means for releasing said bill member.

7. In a chain holding hook structure, the 110 combination with pivotally connected shank and bill members, a keeper for holding said bill member in a chain holding position, a cam for releasing said keeper from said bill member, and a trip arm fixedly secured to said cam thereby insuring a correct position of said trip arm when said structure is adjusted into a chain holding position.

In testimony that I claim the foregoing as my own, I hereby affix my signature.

ANDREW F. ANDERSON.
